UNITED STATES PATENT OFFICE.

ALFRED B. FOWLER, OF CENTRAL FALLS, RHODE ISLAND.

MOTOR-VEHICLE.

SPECIFICATION forming part of Letters Patent No. 690,849, dated January 7, 1902.

Application filed February 23, 1901. Serial No. 48,498. (No model.)

To all whom it may concern:

Be it known that I, ALFRED B. FOWLER, a citizen of the United States, residing at Central Falls, in the county of Providence and State of Rhode Island, have invented certain new and useful Improvements in Motor-Vehicles; and I do hereby declare the following to be a full, clear, and exact description of the invention, such as will enable others skilled in the art to which it appertains to make and use the same.

The present invention relates to motor-vehicles, and more particularly to a motor suspension device for the same.

15 The object of the present invention is to provide a motor suspension device so constructed and arranged that the motor and connections supported thereon shall move as one body and the alinement of the different parts 20 shall not be disturbed, no matter what the quality of the road or the speed of the vehicle.

To the above end the present invention consists in the motor suspension device herein-after described and claimed.

25 In motor-vehicles as first constructed the motor and its connections were mounted directly upon the running-gear without springs. This construction, however, was soon abandoned, and at the present time the usual practice is to mount these parts upon the vehicle-body itself or upon a spring-supported frame. Both of these methods are objectionable, for the relative movements of the vehicle body or frame and of the running-gear constantly 30 throw the driving-shaft and the driven axle out of alinement, making some form of flexible connection necessary. Where the separate frame has been rotatably mounted at its rear end upon the driven axle and the forward end connected to the body of the vehicle, so that it is supported by the forward vehicle-springs or is connected to the front axle and has independent springs, the driving-shaft and driven axle will be held in approxi- 35 mately proper alinement. The other bearings, however, will be thrown out of line by any twisting or warping of the frame caused by one wheel passing over an obstacle.

40 In Figure 4 of the accompanying drawings is shown, diagrammatically, the effect in such a method of suspension if one front wheel

passes over an obstacle six inches in height. If *c*, *d*, and *e* represent points upon the vehicle-body upon which the front end of the suspension-frame is mounted, assuming the vehicle-body to be rigidly supported upon the front axle, it will be evident that as the front wheel passes over the obstacle these points will be moved to the new positions indicated by *c'*, *d'*, and *e'*, respectively. Resolving these movements into their vertical and horizontal components it will be seen that the point *c* has moved vertically through a distance represented by *c'c* and horizontally through *c'c'*, *d* has moved vertically through *d'd* and horizontally through *d'd'*, and *e* vertically through *e'e* and horizontally through *e'e'*. While the horizontal components of these three movements are necessarily all the same, it is evident that the vertical components will and 55 must vary. The same is true if one rear wheel be raised, as similar relative movements are produced. Hence in a four-point suspension device the passing of one wheel over an obstacle will cause a twisting or warping of such a frame, one corner being lifted more than the other, while at the same time one entire end of such a frame will be moved horizontally through a considerable distance. The interposition of springs, either the vehicle-springs or independent frame-supporting 60 springs, will only partially relieve these twisting and racking movements, and the various parts supported on such a frame will be constantly thrown into and out of alinement. 65 In my improved motor suspension device I have overcome these objectionable features; and my invention, broadly speaking, consists in providing a single pivotal support for one end of the frame, which will permit relative 70 longitudinal tipping of the frame and of the body or axle of the vehicle, and in also providing means whereby one end of the frame may move horizontally relative to the body or axle. 75

95 In the illustrated embodiment of my invention, Fig. 1 is a top plan view of the running-gear of a motor-vehicle provided with my improved suspension device, Fig. 2 showing the same in side elevation. Fig. 3 is an 100 enlarged view, partly in section, of the bracket and bearing for the forward end of my sus-

pension device. Fig. 4, as already explained, is a diagrammatic view showing the effect of a forward wheel passing over an obstacle.

In the drawings, 1 represents the running-gear of a motor-vehicle supported upon the axles 2 and 3 by the springs 4 and 5. 6 represents the motor suspension-frame, which is rotatably mounted upon the rear axles 2 by means of the T connections 7. Longitudinal movement of the axle is prevented by means of the collars 8, provided with the set-screws 9. A brace or strut 10 connects the side bars of the frame near their rear end. At their forward end they are connected by the piece 11, which is provided at its middle with the stud 12, carrying the antifriction-roll 13. Secured to the running-gear at the forward end is the bracket 14, provided with the bosses 15, in which are the bearings 16. Mounted in 20 these bearings and arranged to have vertical movement therein are the rods 17, which are provided at their lower ends with a horizontal bearing 18. A compression-spring 19, engaging at one end the top of the boss 15 and at the other the collar 20, pinned to the upper end of the rod 17, permits vertical movement of the bearings 18 to prevent sudden shock when the vehicle passes over some obstacle. The supporting-piece 21 is provided 25 with a slot 22, in which moves the antifriction-roll 13 on the stud 12. Trunnions 23, mounted in the bearings 18, permit movement of this supporting-piece about a horizontal axis as the springs are compressed and expanded. It is to permit this relative vertical movement of the bracket and the supporting-piece that the frame is rotatably supported upon the driven axle.

When one front wheel of the motor-vehicle runs over some obstruction, the springs 19 first take up the sudden shock, allowing a relative vertical movement of the bracket and the slotted support 21, which support turns slightly in the bearing 18 to compensate for the angular movement about the rear axle 2. At the same time the inclination of the front axle and, to a smaller extent owing to the vehicle-springs, of the forward part the running-gear and the bracket 14, supported there-by, has no tendency to twist the suspension-frame 6, as this is pivotally supported by the rolls 13 on the stud 12. The horizontal movement, however, represented in the diagram by the distance $c c'$, effects a relative horizontal movement of the stud 12 and the slotted support 21. It will thus be seen that the horizontal movement as well as the varying vertical movements are provided for and that the frame 6 will be supported without twisting or strain and that the motor and its connections mounted therefrom will remain in perfect alinement with each other and with the driven axle.

Having thus described my invention, I claim as new and desire to secure by Letters Patent—

1. A motor suspension device for motor-

vehicles, having, in combination, a motor-supporting frame mounted at one end upon the driving-axle of the vehicle, and a support for the other end of the frame constructed and arranged to permit relative lateral horizontal movement of the end of the frame and the support, and longitudinal tipping movement of the frame in a plane substantially at right angles to the driving-axle, substantially as described.

2. A motor suspension device for motor-vehicles, having, in combination, a motor-supporting frame mounted at one end upon the driving-axle of the vehicle, and a support for the other end of the frame constructed and arranged to permit relative lateral horizontal movement of the end of the frame and the support, and lateral and longitudinal tipping movements of the frame and the other axle of the vehicle, substantially as described.

3. A motor suspension device for motor-vehicles, having, in combination, a motor-supporting frame mounted at one end upon one axle of the motor-vehicle and a support for the other end of said frame arranged to tip in a plane substantially at right angles to said axle, substantially as described.

4. A motor suspension device for motor-vehicles, having, in combination, a motor-supporting frame mounted at one end upon the driving-axle of the vehicle, a stud mounted upon the other end of the said frame, a support for the stud arranged to permit relative, laterally-tipping movements of said frame and the support, and bearings arranged to permit the support to tip in a plane substantially at right angles to the driving-axle of the vehicle, substantially as described.

5. A motor suspension device for motor-vehicles, having, in combination, a motor-supporting frame rotatably mounted at one end upon the driving-axle of the vehicle, a stud mounted on the other end of said frame, a roll on said stud, and a slotted support for said roll, substantially as described.

6. A motor suspension device for motor-vehicles, having, in combination, a motor-supporting frame rotatably mounted at one end upon the driving-axle of the vehicle, a stud mounted on the other end of said frame, a roll on said stud, and a tipping slotted support for said roll, substantially as described.

7. A motor suspension device for motor-vehicles, having, in combination, a motor-supporting frame rotatably mounted at one end upon the driving-axle of the vehicle, a stud mounted on the other end of said frame, a roll on said stud, a tipping slotted support for said roll, and spring-sustained bearings for said support, substantially as described.

In testimony whereof I affix my signature in presence of two witnesses.
